CLAIM

The ornamental design for a step machine, as shown and described.

DESCRIPTION

FIG. 1 is a front perspective view of a step machine, showing my new design;

FIG. 2 is a rear perspective view thereof;

FIG. 3 is a front elevational view thereof;

FIG. 4 is a rear elevational view thereof;

FIG. 5 is a left side view thereof, the right side view thereof being a mirror image of FIG. 5;

FIG. 6 is a top plan view thereof;

FIG. 7 is a partial enlarged view of FIG. 1;

FIG. 8 is a partial enlarged view of FIG. 1;

FIG. 9 is a partial enlarged view of FIG. 2;

FIG. 10 is a partial enlarged view of FIG. 2;

FIG. 11 is a partial enlarged view of FIG. 3; and,

FIG. 12 is a partial enlarged view of FIG. 5.

The dashed lines in the figures are for the purpose of illustrating portions of the step machine, which form no part of the claimed design.

The dash-dot-dot lines in the FIGS. 2 and 4 are for the purpose of illustrating portions of the step machine, which form no part of the claimed design.

The dash-dot-dash lines are for annotating enlarged views, which form no part of the claimed design.
